UNITED STATES PATENT OFFICE.

THOMAS KEPPEL NORTH, OF WESTMINSTER, LONDON, ENGLAND, ASSIGNOR TO
VICKERS LIMITED, OF WESTMINSTER, ENGLAND.

MOUNTING FOR AUTOMATIC GUNS.

1,304,591.

Specification of Letters Patent. Patented May 27, 1919.

Application filed June 21, 1917. Serial No. 176,060.

To all whom it may concern:

Be it known that I, THOMAS KEPPEL NORTH, a subject of the King of Great Britain, residing at Vickers House, Broadway, 5 Westminster, in the county of London, England, have invented certain new and useful Improvements in or Relating to the Mountings of Automatic Guns, of which the following is a specification.

10 This invention relates to the mountings of automatic guns.

According to the invention there is interposed between the training socket and the training spigot or pivot pin a resilient ring 15 which is adapted to be pressed firmly against the spigot, for holding the gun at any desired angle of training, by a radially disposed screw carried by the socket. By these means the liability of the spigot becoming 20 damaged by contact of the screw with the spigot is avoided. The said interposed ring is preferably split transversely as is well understood and is preferably of wedge shape in cross section, the spigot being formed 25 with a circumferential groove of similar shape to accommodate the said ring.

The horizontal pivot or trunnion pin of the gun is provided with a plate clutch preferably composed of alternate plates of steel 30 and bronze, one series of plates being carried by a part moving with the gun in elevation and the other series by a fixed part; the former part may be constituted by a collar having on its inner surface a projection for engaging with a slot formed in the gun clip and the fixed part may be constituted by the aforesaid horizontal pivot or trunnion pin which is keyed or otherwise detachably connected to the crosshead. The collar incloses 35 the plates of the clutch and thereby protects them against dust and water. Suitable means are provided for varying the pressure between the plates to suit different requirements; that is to say the plates can be caused to hold the gun rigid at any adjusted angle of elevation, to frictionally hold the gun so that some effort is required to elevate or depress it, or to render the gun free so that it can be elevated or depressed with ease.

40 In order that the said invention may be clearly understood and readily carried into effect, the same will be described more fully with reference to the accompanying drawing in which:—

45 Figure 1 is an end elevation showing the

crosshead and the lower part of a gun provided with our improvements.

Fig. 2 is a plan of the aforesaid split ring for engaging with the training spigot or pivot pin. 60

Fig. 3 is a section taken on the line 1—1 of Fig. 2, and

Fig. 4 is a side view showing the aforesaid plate clutch and the collar that incloses it.

Referring to Fig. 1, A is the lower part of 65 the gun, and a is the horizontal pivot or trunnion pin. B is the training spigot or pivot pin and B' is the aforesaid split ring. C is the crosshead, C' is the socket for the training spigot or pivot pin, and C² is the 70 radially disposed screw carried by the socket.

In the example shown the gun is supposed to be of the Lewis type, and has a gun clip comprising two downwardly projecting lugs a', a' between which the upper end of the 75 crosshead C is disposed and through which and the said upper end, the horizontal pivot or trunnion pin a passes; this trunnion pin is connected to the upper end of the crosshead by a pin a² or otherwise. The training spigot or pivot pin B is stationary and is formed with a circumferential groove b of wedge shape to receive the aforesaid split ring B' which is of similar shape but when in position its inner surface lies some 80 distance from the bottom of the groove b. The socket C' has a boss c' which is formed with a screw threaded hole for the reception of the aforesaid radially disposed screw C². The inner end of this screw is reduced in 85 diameter and the outer end carries an actuating handle c². By displacing the handle c² in the proper direction the split ring B' can be pressed firmly into the groove b and the socket C' is then clamped to the training 90 spigot or pivot pin B. It will be obvious that although the ring B' is shown as being applied to a mounting in which the socket C' moves with the gun in training and the training spigot or pivot pin B is stationary, 95 it could be employed in connection with a mounting having a fixed socket and a training pivot pin moving with the gun in training.

D, D' are the aforesaid clutch plates and 100 D' is the collar that incloses them. These plates are as aforesaid composed of two series one of steel and the other of bronze; one of these series has projections d, d (Fig. 4) engaging with keyways in the horizontal 110

5 pivot or trunnion pin *a* and the other has a projection *d** engaging with a keyway formed on the inner surface of the collar *D'*. This collar has a stud *d'* engaging as
10 shown with a slot in the gun clip *a'*. One series of plates thus moves with the gun during elevation and the other series remains stationary. The horizontal pivot or trunnion pin *a* is screw threaded to receive a wing nut *a'* by which the pressure between the plates can be varied to suit different requirements as aforesaid.

What I claim and desire to secure by Letters Patent of the United States is:—

- 15 1. In a mounting for an automatic gun, the combination with the training socket and the training spigot or pivot pin, of a resilient ring which is interposed between the socket and the spigot and a radially disposed screw carried by the socket and serving by its pressure on the ring to press the latter firmly against the spigot.
- 20 2. In a mounting for an automatic gun, the combination with a training spigot or pivot pin having a circumferential groove of wedge shape, of a resilient ring of similar shape and an actuating device for pressing said ring into the groove.
- 25 3. In a mounting for an automatic gun, the combination of a support, a horizontal pivot pin stationarily mounted thereon, a

member pivotally mounted on the pin and moving with the gun when training the gun in elevation, two series of clutch plates mounted on the pin and one connected to the 35 pin and the other to said member, and a member mounted on the pin and operable to subject the series of plates to pressure.

4. In a mounting for an automatic gun, the combination of a support, a horizontal pivot pin stationarily mounted thereon, a member pivotally mounted on the pin and moving with the gun when training the gun in elevation, two series of clutch plates mounted on the pin and one connected to the 40 pin and the other to said member, and means which is independent of the movement of the gun and said member and which is operable to subject the two series of plates to pressure.

5. In a mounting for an automatic gun, the combination with the fixed horizontal pivot or trunnion pin of the gun, of a plate clutch comprising two series of plates one of which is connected to the said horizontal 55 pivot, and a collar which is connected to the gun and to which the other series of plates is connected, this collar inclosing both series of plates.

In testimony whereof, I affix my signature.

THOMAS KEPPEL NORTH.
